(57) **CLAIM**

The ornamental design for shotgun, as shown and described.

DESCRIPTION

This application is also related to U.S. patent Nos. 6,877,265 and 7,380,361.

FIG. 1 is a perspective view of the shotgun showing a new ornamental design thereof;

FIG. 2 is a right side elevation view of the shotgun shown in FIG. 1;

FIG. 3 is a left side elevation view of the shotgun shown in FIG. 1;

FIG. 4 is a top plan view of the shotgun shown in FIG. 1;

FIG. 5 is a bottom plan view of the shotgun shown in FIG. 1;

FIG. 6 is a front elevation view of the shotgun shown in FIG. 1;

FIG. 7 is a rear elevation view of the shotgun shown in FIG. 1;

FIG. 8 is a perspective view of an alternate embodiment of the shotgun shown in FIG. 1;

FIG. 9 is a right side elevation view of the shotgun shown in FIG. 8;

FIG. 10 is a left side elevation view of the shotgun shown in FIG. 8;

FIG. 11 is a top plan view of the shotgun shown in FIG. 8;

FIG. 12 is a bottom plan view of the shotgun shown in FIG. 8;

FIG. 13 is a front elevation view of the shotgun shown in FIG. 8; and,

FIG. 14 is a rear elevation view of the shotgun shown in FIG. 8.

The design is shown broken apart in FIGS. 8–14 to indicate that no specific length is claimed.
